Elgar Williams

United States Patent Office.

ELIJAH WILLIAMS, OF MARIANNA, FLORIDA.

Letters Patent No. 64,392, dated April 30, 1867.

IMPROVEMENT IN PROPELLING BOATS.

The Schedule referred to in these Letters Patent and making part of the same.

Be it known that I, ELIJAH WILLIAMS, of Marianna, Jackson county, Florida, have invented a new and improved Machine for Propelling Flat-Boats, Canal-Boats, Scows, and Gondolas, or other similar water crafts; and I do hereby declare that the following is a full, clear, and exact description of the construction and operation of the same, reference being had to the annexed drawings, in which—

Figure 1 is a side elevation.

Figure 2 is a view looking down upon it from a point directly over its centre.

A represents the deck of the boat; B B, paddles or other wheels, of any ordinary construction; C is a shaft; D is a ratchet-wheel; E is a pinion-wheel; F is a driving-wheel; f f, cogs in driving-wheel; G G, levers; g, pivot fulcrum of levers; H H, adjustable screws; I, platform on which machinery rests, and to which it is attached; K, crank-wheel; L, shaft of ratchet-wheel D; M, post supporting ratchet-wheel D; N, post supporting driving-wheel F; O O, pawls; P P, springs to press down the pawls.

To enable others skilled in the art to make and use my invention, I will proceed to describe its construction and operation.

The object of my invention is to actuate rotary motion for the purpose of propelling boats by means of levers operated by man or horse power. To accomplish this, to the shaft C, attached to the wheels B B, I at any suitable point firmly fix a pinion-wheel, in the teeth of which plays a ratchet-wheel, D, of any desired diameter, supported by a shaft, L, resting in post M, of which but one can be exhibited in the drawings. To the shaft L is attached a pinion-wheel, E, in which play the teeth of a driving-wheel, F, which is supported by a shaft, L, working in the post N. To each flat surface of the driving-wheel F I firmly attach a wheel, f f, of less diameter than the driving-wheel, in the periphery of each of which cogs are cut. These wheels may be cast or otherwise made as parts of the driving-wheel. In each of these wheels works one end of a pawl, O, the other end being attached to a lever. These pawls are pressed upon the cogs by a spring, P P, which also is fixed to the lever. On lifting alternately the free ends of the levers the teeth of the pawls slide back over the cogs, and on depressing them the teeth catching in the cogs cause the driving-wheel F to revolve and thus set the wheels B in motion, propelling the boat connected with the wheels. When desired the wheels may be detached from the cogs by raising and suspending the pawls by chains, as exhibited in the drawings.

The levers should be operated alternately, one being raised while the other is being depressed. They may be operated by man power in the ordinary manner, or by man or horse power turning a crank-wheel working in slots cut through the free ends of the levers. The fulcrum g of the levers may be placed where represented in the drawings, or at or near the foot of the post N. It may be necessary to elevate or depress the wheels B B as the boat is more or less deeply laden. To accomplish this I attach my machinery to a platform, I, which is fixed to the deck A of the boat by means of vertically adjustable screws H H H, the lower ends of which are firmly fastened in the deck A of the boat, and on the upper ends of which nuts work. By turning up the nuts the platform I may be raised, and it may be kept in its place by means of blocks placed under it. To depress the wheels I move the blocks and reverse the operation of the nuts. To reverse the motion of the boat the levers may be detached, as before described, and the machinery backed by means of a crank-wheel, K, attached to the shaft L.

My invention will be found of great service on shallow water, where steam cannot be used to advantage; and where boats and scows are now propelled by poles. By the use of my invention four men easily may perform the labor which now requires twelve, and at a light expense for machinery.

What I claim as my invention, and desire to secure by Letters Patent, is as follows:

1. The combination of the pawls C O, with the springs P P, and the driving-wheel F, the pinion-wheel E, the ratchet-wheel D, and the paddle-wheels B B, all constructed and operated substantially in the manner and for the purposes hereinbefore set forth.

2. I claim, in combination with the above, the method of elevating and depressing the paddle-wheels by means of a platform operated by adjustable screws and blocks, substantially in the manner and for the purposes above set forth.
